C. DUCAS

FORCED DRAFT DEVICE

Filed Sept. 1, 1926

INVENTOR
Charles Ducas,
BY

Harold D. Penney, ATTORNEY

UNITED STATES PATENT OFFICE.

CHARLES DUCAS, OF NEW YORK, N. Y.

FORCED-DRAFT DEVICE.

Application filed September 1, 1926. Serial No. 132,994.

My present invention relates to an improvement in forced draft devices known as exhaust or jet nozzles, such as are used for creating artificial or forced draft in steam boiler fire boxes, and especially adapted to utilization in locomotive boilers.

One of the distinct advantages of my construction, relates to the provision, in a device of this kind, of an annular jet or blast port 10 whereby exhaust steam from the cylinders may be passed up through the stack of the locomotive to create a forced draft, by jet or aspiration action, through the fire box, and the stream of exhausting steam is directed in 15 a hollow conical form thereby creating a draft of air in a highly efficient manner. It has been ascertained that this form of hollow annular stream of steam readily entrains a large amount of fire-box gases and carries them upward and outwardly through the stack, through its greatly increased area of contact with the gases, by reason of the interior and exterior surfaces presented by the hollow annular steam jet, so formed.

20 Another advantage relates to the structure of the nozzle itself, in which all of the foregoing features are accomplished by a single, unitary structure, having a minimum number of required connections to the steam and exhaust end of the boiler and cylinders, making for ease of manufacture, installment and replacement.

These and other features and capabilities will be ascertained as the disclosure proceeds 35 and I do not desire to be limited to the details thereof as it is obvious that modifications may be made in the structural details, without departing from the scope of the invention as herein claimed.

40 Fig. 1 is a sectional view of a conventionalized locomotive boiler showing my device in operative position, and partly in action.

Fig. 2 is a plan view of my device.

45 Fig. 3 is a sectional view thereof taken on the line 3—3 of Fig. 2, looking in the direction of the arrow.

Fig. 4 is a bottom view of my device, and

Fig. 5 is a partial sectional elevation from the front or steam jet end.

50 In ordinary installations of a device of

this kind it is customary to place this device immediately and axially under the stack S, Fig. 1 which is a complementary portion of the boiler, generally denoted by B. The boiler and its component parts are obviously 55 shown in conventional form for the purpose of illustration and comprises heating tubes T, which pass through the baffle or head wall B' in the usual structural practice.

For the sake of convenience and brevity I 60 have omitted the steam cylinders and connections therefrom whereby the draft creating steam is delivered to the draft nozzle, as these are well known features and are readily understood.

65 By referring to Fig. 1, my draft or exhaust nozzle, generally denoted by N, is located, preferably, upon a suitable seat, within the boiler and by means of a flange 1 may be bolted or otherwise fastened through the bolt 70 holes 2, Fig. 4 to said seat, not shown, which constitutes the top of the exhaust saddle from the engine cylinders.

75 There is also provided a downwardly formed gas or combustion deflecting baffle Y, Fig. 1, which compels the gases of combustion, as they pass through the heating tubes T, to be deflected downwardly and forwardly about the nozzle N in the direction of the arrows A, around and about the exhaust 80 nozzle N; this baffle Y is preferably here connected to the nozzle N so as to entirely enclose and divide the front end of the boiler into two chambers, V the upper and W the lower, and the forward end of the baffle, is so 85 constructed as to support and operatively hold therein a spark arrester screen, as denoted by X, through which the combustion gases pass, as indicated by the arrows, under the aspiration of the forwardly moving 90 steam jet 14.

95 By referring to Figs. 3 and 5, it will be noted that substantially at or a little lower than, the middle of the nozzle N there is provided on opposite sides two opposing entry ports 3 and 4 respectively thereby bifurcating the nozzle at its interior at this point, and these interior ports merge by an easy curve into a single central upwardly directed emission port 5. Just below this port and, prefer- 100

ably integral therewith is arranged a steam inlet duct, generally denoted by 6, which terminates at its inner end into a steam jet nozzle 7 which nozzle is located substantially centrally of the nozzle N and of its upwardly directed jet nozzle port 5. This duct 6 is threaded at one end as at 8 in order to receive therein a valved steam pipe connection from the boiler, or other controlled pressure source, whereby steam or air may be introduced therein to create a starting blast for causing a draft up through the stack S, or may be utilized, ordinarily, when the engine is at a standstill, by the opening of a suitable steam controlling valve, not shown.

For the purpose of creating a draft during operation of the locomotive, by means of the exhaust steam from the cylinders, an outer nozzle is provided with two ports 9 and 10 at its lower end or base 1, these ports being connected to the opposite locomotive steam cylinders, not shown, whereby during the operation of the cylinders, exhaust steam is intermittently introduced into these opposite ports, whence they pass upwardly and merge into a common chamber, generally denoted by 11 at the upper end thereof, around and above the ports 3 and 4.

At the upper end of this outer chamber 11 and suitably and firmly mounted thereon is an annular jet cap 12 which is so proportioned that it leaves an annular exhaust steam opening 13 whereby the steam emits there-through at high velocity. This steam as it emits upwardly, expands hollow and cone-like, as indicated by dotted lines 14 and it will be noted that as it reaches the upper end of the stack S that it practically fills the central portion of the stack to the outer upper edges thereof and that during such action it will create a draft as previously described.

The inner jet nozzle 7 creates an upward blast of air or steam, generally denoted by 15, Fig. 1 at the dotted lines and this serves the purpose as herein described for creating a draft when starting the fire, or when the locomotive is standing still.

It is obvious from the foregoing description that I have provided a draft creating nozzle that is unitary in its structure and is arranged so as to increase the area of gas contact with the steam jet as it aspires, and contracts with the boiler gases.

The increased exhausting effort is accomplished by the structural features of the annular jet nozzle 12, the annular jet port 13, the interior uprising chamber 5, with its gas inlet ports 3 and 4, whereby there is added to the outer surface of the steam exhaust jet 14, an interior surface area thereof. This causes added contact areas of gas and steam and greatly increases the draft in the firebox.

Having thus disclosed my invention, what I claim is:

1. In an exhaust nozzle, in combination, a boiler chamber having a discharge stack, means for passage of the gases of combustion from the heating means of the boiler into said boiler chamber, a nozzle disposed in said boiler chamber for cooperation with said stack and having a central chamber provided with a circular discharge opening and having ports for entrance of gases of combustion from the boiler chamber into said central chamber, an annular chamber disposed around said central chamber and having an annular discharge opening and an annular jet cap for the ends of said central and outer chambers, said cap having a relatively large circular opening for discharge of gases of combustion from the central chamber and projecting across the outlet of said annular steam chamber so as to leave a narrow annular opening around and adjacent to said circular opening for discharge of steam from the outer chamber at high velocity, passages connecting said annular chamber with engine cylinders appurtenant to the boiler for providing unbroken passage of steam from said cylinders to said annular discharge opening, the steam discharged from said annular opening being in the form of a hollow cone, the gases of combustion being drawn from the boiler chamber through said inlet ports of the central chamber by entrainment of said hollow cone of steam and discharged through said circular outlet opening of the central chamber in the form of a column of gases of combustion surrounded by the hollow cone of steam, and a jet located in the axial line of said nozzle at the bottom of said central chamber adjacent to the inlet ports thereof and connected to the steam generating means of the boiler for projecting a stream of steam into said chamber whereby the gases of combustion are drawn through said ports and discharged through said circular outlet in a column of mingled gases and steam by entrainment of said stream of steam for providing draft when said engine cylinders are not operating.

2. In a nozzle, in combination, a base, an inner housing circular in cross-section disposed on said base and forming a central chamber having a pair of oppositely disposed intake ports for gases of combustion, an outer housing disposed around the inner housing and forming an outer chamber having an annular portion around the central chamber above said intake ports and having on sides of the outer chamber opposite said intake ports of the central chamber oppositely related extensions of the outer chamber terminating at said base, means for connecting the end of each of said extensions adjacent said base to the exhaust of an engine cylinder, said extensions and connecting means providing unbroken passage for steam from each cylinder to said annular portion

of the outer chamber, and an annular jet cap for the ends of said central and outer chambers opposite said base, said cap having a relatively large circular opening for discharge of gases of combustion from the central chamber and projecting across the outlet of said annular steam opening so as to leave a narrow annular opening around and adja-

cent to said circular opening for discharge of steam from the outer chamber at high ¹⁰ velocity.

Signed at New York, in the county of New York and State of New York, this 28th day of August, A. D. 1926.

CHARLES DUCAS.
